[21] Appl. No.: 94,979

[57] **CLAIM**

The ornamental design for a bottle, as shown.

[22] Filed: Nov. 16, 1979

DESCRIPTION

FIG. 1 is a top plan view of a bottle showing our new design;

FIG. 2 is a side elevational view;

FIG. 3 is an elevational view looking from the right of FIG. 2, the opposite side being a mirror image thereof;
FIG. 4 is an elevational view showing the side opposite that seen in FIG. 2; and

FIG. 5 is a bottom plan view.
